METHOD OF FORMING A STARTING COURSE IN KNITTED FABRIC

Karl R. Lieberknecht, Oberlungwitz, Germany,
assignor to Kalio, Inc., New York, N. Y., a
corporation of New York

Application November 11, 1933, Serial No. 697,555

1 Claim. (Cl. 66—90)

This invention relates particularly to the formation and manipulation of the starting course at the beginning of the welt of a full fashioned stocking knit upon a flat knitting machine. However, it may be utilized wherever a starting course is required and in connection with other knitted fabrics as well as stockings. With this understanding the description will be limited to the starting course of the welt of a stocking.

It has long been the practice after the yarn for the starting course of the welt of a full fashioned stocking knit upon a flat knitting machine has been laid down and divided to pick up the sinker loopers by a welt bar and to utilize this bar for preserving the starting course loops until the welt is turned and the starting course knit or looped to the leg fabric. Ordinarily the welt turning is performed at the completion of the welt, the starting course loops being then transferred from the welt bar back onto the needles so that the first course of the leg will complete the welt by looping the first and last welt courses together. The loops of the starting course being extremely small it is a difficult task to properly transfer all of these loops from the welt bar back onto the needles and failure to accomplish this perfectly has resulted in much imperfect fabric.

The object of this invention is to provide a method for simplifying and improving the welt turning process by forming the first course in a semi-automatic manner so that it is composed of longer and wider loops which may be much more easily transferred from the welt bar back onto the needles.

A further object is the provision of a method of accomplishing this through the employment of attachments with which the knitting machine is normally provided and in particular the narrowing or picot mechanisms.

The nature of the invention will be clearly understood from the following description taken in connection with the drawing, of which

Figure 1 illustrates diagrammatically the loops of the starting course of a stocking or other fabric after they have been formed around the needles by the sinkers;

Fig. 2 illustrates the same starting course after every other loop has been hooked onto a welt bar, the intervening loops having disappeared and the remaining loops correspondingly lengthened;

Fig. 3 illustrates the loops in the same condition as in Fig. 2 with the exception that the

narrowing or picot mechanism has been brought in play in such a way that a picot point is now interposed between the yarn and one of the two needles around which each loop passes;

Fig. 4 illustrates the next step in the method in which the picot point has operated to lift the yarn from one needle and in effect to transfer it to the other needle of the pair; and

Fig. 5 illustrates the next step in which the starting course formed and described above is knit to the following course.

As shown in Fig. 1 the starting course loops 1 are laid and sinkered around each needle 2 in the customary manner. The sinkers are diagrammatically shown at 3. If prior practice were followed each of the sinker loops 4 thus formed would be hooked onto a welt bar. By the method of this invention the welt bar instead of being provided with a hook for each loop has only half as many hooks, one for every other sinker loop as shown at 5 in Figs. 2-5. Consequently when the loops of the starting course formed as described above are hooked to the welt bar only every other loop will be caught. Therefore, the remaining alternate loops will disappear as shown in Fig. 2 leaving a series of loops wider and longer than normal, each passing around two adjacent needles and each being separated by a sinker loop of substantially normal width but greater than normal length 30 caught by a welt hook.

The next step in the formation of the starting course diagrammatically illustrated in Figs. 3 and 4 is the lifting of the yarn from one needle of each of the above pairs, leaving each loop held by a single needle and by the welt bar as shown in Fig. 4. This may be accomplished automatically by employing the picot bar of the knitting machine. As is well known such a picot mechanism is provided with a number of points so operated as to engage with certain of the needles to lift the loops from those needles and to transfer them to adjacent needles. In this instance the picot mechanism may be employed to lift the loops from one of the needles of each of the pairs 45 around which the needle loops of the starting course now pass as above described, and, in effect, to transfer these loops to the other needle of the pair.

Since there is no sinker loop between the two 50 needle loops this has the effect of dropping the loop from every other needle. This step is diagrammatically illustrated in Figs. 3 and 4, the picot bar points being numbered 6. In Fig. 3 they are shown between the first and every al-

ternate needle and the yarn passing therearound. In Fig. 4 the picot points have operated to lift the yarn from around these needles and carry it over to the alternate needles leaving the yarn suspended only from those needles. This results in loops of double width and of considerably greater length than normal loops.

10 The knitting of the second course of the welt then proceeds in the normal manner, the special loops described above being knit to the loops 7 of the second course in the usual way as shown diagrammatically in Fig. 5.

15 When the knitting of the welt is completed it is turned in the usual manner and the loops of the first course transferred from the welt bar hooks back onto the needles. Since these loops are of greater width and length than normal this operation is effected with much greater ease and certainty than by the prevailing practice. Also, 20 with the exception of the attaching of the welt bar and the transferring of the loops back onto the needles which is still performed in substantially the standard manner, the forming of the enlarged loops is carried out automatically by 25 means of standard machine attachments with the result that the method not only insures perfect results but greatly expedites the loop forming

and welt turning operations, thus increasing the productive capacity of the machine. The method may be applied not only to the beginning of the welt but to any other part of the stocking where a stocking course is required and, of course, it may be used with equal facility in connection with other knitted fabrics.

5 What I claim is:

10 The method of producing a starting course on a flat knitting machine which consists of forming needle loops around all of the needles, dropping alternate sinker loops and lengthening the remaining sinker loops, thereby absorbing the slack so that each needle loop passes around two needles, all while the needles are performing the regular motions of a knitting cycle and then before the beginning of another knitting cycle and while the needles are performing their regular motions of a narrowing cycle inserting a point 15 between each needle loop and one of the needles of the pair around which the loop is formed, lifting the loop from this needle by the point and then removing the point from the loop leaving it around the remaining needle of the pair and then looping the needle loops to a second course 20 of regular loops during the next knitting cycle.
